VACUUM FURNACE FOR DENTAL RESTORATIONS

Nat Gold, Newark, N.J., assignor to Nu-Dent Porcelain Studio Inc., New York, N.Y., a corporation of New York

Filed Nov. 8, 1960, Ser. No. 62,773

Term of patent 14 years

(Cl. D81—20)

FIG. 1

FIG. 2

FIG. 3

FIG. 1 is a front perspective view taken from the top and left side of a vacuum furnace for dental restorations embodying my new design, the rear and right side not shown being substantially plain.

FIG. 2 is an end elevational view thereof; and

FIG. 3 is a top plan view thereof.

I claim:

The ornamental design for a vacuum furnace for dental restorations, as shown and described.
